UNITED STATES PATENT OFFICE.

AXEL JULIUS LAURITS LASSEN, OF COPENHAGEN, DENMARK.

MACHINE FOR CLOSING BOTTLES AND THE LIKE WITH CAPSULES.

1,224,937.

Specification of Letters Patent.

Patented May 8, 1917.

Application filed July 16, 1915. Serial No. 40,209.

To all whom it may concern:

Be it known that I, AXEL JULIUS LAURITS LASSEN, a citizen of the Kingdom of Denmark, residing at No. 5 Aaboulevard, Copenhagen, Denmark, have invented certain new and useful Improvements in Machines for Closing Bottles and the like with Capsules, of which the following is a specification.

This invention refers to a machine for 10 capsuling bottles and like receptacles (both such as contain liquids under pressure, for instance beer, and such as contain liquids not subjected to pressure, for instance milk), the capsuling being accomplished by means 15 of capsules of some suitable metal eventually lined with some soft packing, or tightening-material, for instance paper, cork, or the like.

Capsuling machines heretofore in use 20 were disadvantageous for the most part because of the ineffectual manner in which the mandrel over which the capsule is shaped is operated. This operation must take place quickly and reliably, and the mandrel must 25 stand steady and firm while the capsule is being shaped over it.

A characteristic feature of the present invention is that the mandrel is swung from below up against the capsule-blank which is 30 disposed under the sleeve-shaped piston-head, the capsule-blank having been previously stamped out by the piston.

The mandrel first presses the blank a short distance up into the piston-head, so 35 that the blank is given the shape of a flattened capsule, and is then swung to one side, after which the bottle (while the capsule-blank is held fast, in the aforesaid position) is carried upward, pressing the capsule- 40 blank still higher up into the hollow piston-head, whereby the capsule-blank is given its final shape and is caused completely to embrace the ridge or flange on the neck of the bottle.

45 In the machine which serves to perform this operation, the mandrel over which the capsule is shaped is made fast to a movable member which can turn around an axle-bolt, or the like, fixed in the machine-frame, 50 and which gets its motive power from the main shaft of the machine.

One form for construction of this machine is shown in the drawing, in which, 55 Figure 1 is a side-view of the machine, partly in section; Fig. 2 is a front view of the same;

Fig. 3 is the mandrel over which the capsule is first shaped, but in another working position than in Fig. 1;

Fig. 4 shows those parts of the machine 60 by means of which the capsule is given its temporary shape (larger scale) and

Fig. 5 shows the parts which serve to press the capsule on to the bottle (also 65 larger scale).

In the frame 1 of the machine there are bearings for the main shaft 2, which is run by means of a pulley 3, and which carries cams, 4, 5 and 6, by means of which the different members of the machine are moved. 70

The cam 4, as shown in Fig. 2, has a groove 7 in which a pin 9, furnished with a roller 8 moves.

The pin 9 is disposed on a crosshead 10 which is guided in a sleeve 11 secured to the 75 machine-frame, the sleeve being adjustable by means of the flanges 12. The crosshead 10 is hollow, and in its hollow part can slide a sleeve 13 which embraces a spiral spring 14 and an ejecting-piston 15.

In the top of the sleeve 13 is screwed a 80 pin 16 projecting through a hole in the crosshead 10 and being actuated, during the revolution of the cam 4 by means of a lug 17 disposed on its periphery (Fig. 2). The movement of the ejecting-piston 15 in the sleeve 13 is limited by means of a bolt 19 passed through an elongated hole 18 and the movement of the sleeve 13 in the hollow 85 part of the crosshead 10 is limited by another bolt 20, which is passed through a similar hole 21 in the sleeve. On the lower part of the crosshead 10, the piston proper 22 is secured by means of a hollow cylinder 23 screwed into the crosshead and furnished 90 with a nut 24.

The piston 22 is hollow and embraces an 95 ejector 25, which by means of a collar 26 rests on the upper edge of the piston, so that it cannot fall out. The ejecting piston 100 15 rests, in its normal position, against the upper side of the ejector 25, as shown in Fig. 1.

Under the piston 22 there is disposed a 105 cutting-ring 28 inserted in a plate 54 whose edge 53 projects a little in front of the edge of the hole in the cutting-ring 28. The plate 54 is carried by a bracket 27 projecting from the machine frame 1, and under the bracket 27 there is a device for guiding the bottles 29, which rest on a table 30, whose carrier-pin 31 can move in a guide 32. The 110

table 30 is raised and lowered by means of a lever 33, capable of turning around a bolt 56 in the bracket 55 carrying the guide 32, and being actuated by a rod 34 which at its 5 top has a roller 35, which is pressed up against the cam 6.

A sector 37, which turns on a bolt 36, which has its bearing in the machine-frame 1, carries a mandrel 38, over which the capsule-blank is given a temporary shape. The mandrel 38 itself is secured to the sector, and, as specially shown by Fig. 3, is surrounded by a ring, namely the removal-ring 39, which, by means of pins 41, rests 15 on the plate 40. The lower surface of this plate is actuated by a pawl 42 rockably disposed in a hollow in the sector 37, said pawl being actuated by a spiral spring 43, in such a manner that it always tends to hold the removal-ring 39 up on a level with the upper surface of the mandrel 38, as 20 shown in Fig. 3.

To the sector 37 is secured an arm 44, and between this arm and the sector there is disposed a roller 45, which is placed on the end of the lever 46. This lever is movable around a pin 47 stationarily disposed in the machine-frame, and is actuated by means of a link 48 from the rod 49, which at its top 30 carries a roller 50 actuated by the cam 5.

Furthermore, the machine is furnished with a device for the automatic feeding of the capsule-blanks. This device, which is not shown on the drawing, is of a kind already 35 known, and will therefore not be described here.

The main shaft 2 is provided with a clutch 51 which, by means of a traction-rod 52 is closed when the machine is started, 40 which may be accomplished either by hand or foot pressure.

The machine works in the following manner:—

During the rotation of the main shaft 45 2, the piston 22 is carried down toward the sheet of metal which is fed in between the piston and the cutting-ring 28 and cuts out the capsule-blank. At the same time that the piston 22 goes down to this position, 50 where it temporarily remains, the sector 37 is turned upward, so that the mandrel 38 is carried up into the hollow part of the piston 22 into the position shown in Fig. 4. The removal-ring 39 is pressed downward 55 by the edge of the piston 22, firmly gripping the cap blank 52, so that the same is stretched by the mandrel 38 to the form or shape of a shallow cup with its bottom turned upward and with a ring-shaped, 60 downward-bent rim. The sector 37 then recedes, and the removal-ring 39 at the same times pushes the blank 52 out over the mandrel 38, so that the blank remains in the lower part of the hollow part of the piston 65 22, where it is frictionally held fast by

means of its own elasticity. For further security, the edge 53 also prevents the blank from falling out of the machine and being lost.

The neck of the bottle 29 is then passed 70 up into the piston 22 in the position shown in Fig. 5. The ejector 25 is pressed a little upward, although the spring 14 still holds it tight down against the capsule, which is thus pressed close down against the mouth 75 of the bottle, and the rim of the capsule-blank 52 is straightened out and caused to hug the neck of the bottle. Finally, when the table 30 is lowered, at the same time that the piston moves upward, the capsuled 80 bottle is removed from the piston 22 by means of the ejector 25 loosening the capsule from the piston, owing to the fact that the sleeve 13, which at this moment is given a pressure by the lug 17 by means of the 85 pin 16, actuates the ejector 25 (on its head 26). Then the capsuling is finished.

Grooves or rifles may be cut on the inner surface of the lower edge of the piston 22 which will stamp the edge of the capsule in 90 such a way that, when it is put in place on the neck of the bottle, its edge will be fluted where it is pressed around the ridge or flange on the neck of the bottle. This capsule has an outer resemblance to the well-known crown cork.

The sealing disk lies on the top of the neck of the bottle, but since the tightening-material, together with the capsule, is also pressed down over the sides of the neck of 100 the bottle, a still tighter and more efficient closing is accomplished.

I claim—

1. A machine for placing capsules on bottles, comprising means for supporting a 105 capsule-blank, a sleeve shaped piston above said blank holder, a mandrel swingingly mounted below said holding means, and adapted to be swung upward against the capsule blank, and to coöperate with said piston to shape said capsule into a relatively shallow capsule pressed into said piston and having a laterally extending rim below said piston, a bottle support adapted to bring a bottle into contact with said capsule upon 110 removal of said mandrel, and to press said capsule and lateral rim into said piston to form the same into a relatively deep capsule embracing the head of the bottle.

2. A machine for placing capsules on 115 bottles, comprising means for supporting a capsule-blank, a sleeve shaped blank-cutting piston above said blank holder, a mandrel swingingly mounted below said holding means, and adapted to be swung upward 120 against the capsule blank, and to coöperate with said piston to shape said capsule into a relatively shallow capsule pressed into said piston and having a laterally extending rim below said piston, a bottle support 125 130

adapted to bring a bottle into contact with said capsule upon removal of said mandrel, and to press said capsule and lateral rim into said piston to form the same into a 5 relatively deep capsule embracing the head of the bottle, and ejecting means within said piston adapted to move said capsuled bottle downwardly from said piston.

3. A machine for placing capsules on 10 bottles, comprising means for supporting a capsule blank, a sleeve shaped piston above said blank, a swinging mandrel holder swingingly mounted upon the machine frame below said blank holder, a main shaft 15 for operating said machine, a lever for swinging said mandrel holder, adapted to be operated from said main shaft, a mandrel stationarily fixed to said mandrel holder, said mandrel adapted to be swung upward 20 against the capsule blank, and to coöperate with said piston to shape said blank into a relatively shallow capsule pressed into said piston and having a laterally extending rim below said piston, a bottle support adapted 25 to bring a bottle into contact with said capsule upon removal of said mandrel, and to press said capsule and lateral rim into said piston to form the same into a relatively deep capsule embracing the head of 30 the bottle.

4. A machine for placing capsules on bottles, comprising means for supporting a capsule blank, a sleeve shaped piston above said blank, a swinging sector-shaped mandrel holder, a mandrel stationarily fixed to said mandrel holder, a removal ring surrounding said mandrel, a spring pressed pawl adapted to yieldingly support said ring so that the upper edge of said ring in its normal position is at a level with the upper edge of the 35 mandrel, said mandrel adapted to be swung upward against the capsule blank, and to coöperate with said piston to shape said blank into a relatively shallow capsule 40 pressed into said piston and having a laterally extending rim below said piston and engaged at its under side by said removal 45

ring, said ring being pressed downwardly with respect to said mandrel, a bottle support adapted to bring a bottle into contact 50 with said capsule upon removal of said mandrel, and to press said capsule and lateral rim into said piston to form the same into a relatively deep capsule embracing 55 the head of the bottle.

5. A machine for placing capsules on bottles, comprising means for supporting a capsule blank, a sleeve shaped piston above said blank, a sector-shaped swinging mandrel holder swingingly mounted upon the 60 machine frame below said blank holder, having a slot therein, a mandrel on said mandrel holder, a main shaft for operating said machine, a lever pivoted to the frame and provided with a roller engaging said 65 slot of said mandrel holder, and adapted to swing said holder by movement in said slot, said lever adapted to be actuated from the main frame, said mandrel adapted to be swung upward against the capsule blank, 70 the transmission of pressure from the mandrel holder to the lever being in the direction of the mandrel engaging arm of the lever toward the pivotal point of said lever, in the working position of said mandrel, 75 said mandrel adapted to coöperate with said piston to shape said blank into a relatively shallow capsule pressed into said piston and having a laterally extending rim below said piston, a bottle support adapted 80 to bring a bottle into contact with said capsule upon removal of said mandrel, and to press said capsule and lateral rim into said piston to form the same into a relatively deep capsule embracing the head of 85 the bottle.

In testimony that I claim the foregoing as my invention, I have signed my name in presence of two subscribing witnesses.

AXEL JULIUS LAURITS LASSEN.
